UNITED STATES PATENT OFFICE.

EDWIN E. WOLF, OF NEW YORK, N. Y., ASSIGNOR TO COLONY CLUB FROCKS, OF NEW YORK, N. Y., A CORPORATION OF NEW YORK.

DESIGN FOR A LADY'S BLOUSE.

Application filed November 6, 1923. Serial No. 7,697. Term of patent 3½ years.

To all whom it may concern:

Be it known that I, EDWIN E. WOLF, a citizen of the United States, and a resident of the city of New York, borough of Manhattan, in the county and State of New York, have invented a new, original, and ornamental Design for Ladies' Blouses, of which the following is a specification, reference being had to the accompanying drawing, forming part thereof, wherein the blouse is distinguished by means of a smooth uninterrupted front and back box-plait effects extending from the shoulders near the neck, overlying the front and extending straight downwardly to the lower edge of the garment, with pocket flaps and cuffs substantially matching the box plaits.

In the accompanying drawing—

I claim:

The ornamental design for a lady's blouse, substantially as shown and described.

EDWIN E. WOLF.
